FASTENING MEANS FOR THE STATOR
PLATES OF FLYWHEEL MAGNETOS

George F. McGrevey, West Springfield, Mass., assignor to Wico Electric Company, West Springfield, Mass., a corporation of Massachusetts

Application December 8, 1949, Serial No. 131,723

5 Claims. (Cl. 171—209)

1

This invention relates to improved fastening means for adjustably holding the stator plate of a flywheel magneto on the pilot flange of the crankcase of an internal combustion engine in such a manner that the stator plate may be manually moved to, and frictionally held in, various positions of angular adjustment on the pilot flange and retained against axial movement or tilting movement thereon.

The invention is an improvement on that disclosed in Patent No. 2,487,095, granted November 8, 1949, on an invention of Allen L. Brownlee and George F. McGrevey, to the assignee of this invention.

The invention is desirable for use with the stator plate of a flywheel magneto, which is to be used on an engine of the variable-spark type, as distinguished from the fixed-spark type. Such a plate, and the stationary magnetic coil-carrying elements of the magneto mounted thereon, must be movable to various angular positions relative to the engine crankshaft in order to vary the timing of the spark produced by the magneto. An outboard motor is one example of an engine of the type described.

This invention has for an object the provision of one or more fastening means units for holding the stator plate of a flywheel magneto to a pilot flange on the crankcase of an internal combustion engine in various positions of angular adjustment, each such unit consisting of a friction shoe, with a spring to press it against the cylindrical surface of the pilot flange, and a spring finger to engage an inner end face of the pilot flange to yieldingly hold the stator plate against axial movement or tilting movement on such flange, both shoe and finger being interconnected for movement into and out of holding position by a single manually-operable means, which is accessible from an outer wall of the stator plate, and is also operable, after having moved the shoe and finger into holding position, to adjust the pressure of the spring which forces the shoe against the cylindrical surface of the pilot flange.

The invention will be disclosed in one illustrative example with reference to the accompanying drawings, in which:

Fig. 1 is a top plan view of a stator plate for use in a flywheel magneto and embodying the fastening means of this invention, a portion of the engine flywheel being shown in section;

Fig. 2 is a sectional elevational view of the stator plate taken on the line 2—2 of Fig. 1 and showing also the pilot flange on the engine crankcase and the engine flywheel;

2

Fig. 3 is a fragmentary sectional view, taken similarly to Fig. 2 but showing one unit of the fastening means in an outer position, in which both shoe and finger are released from engagement with the pilot flange;

Fig. 4 is a fragmentary sectional plan view taken on the line 4—4 of Fig. 2 and showing the shoe portion of one unit of the fastening means together with its spring and manual-operating means;

Fig. 5 is a fragmentary bottom plan view of the stator plate showing the spring finger portion of one unit of the fastening means;

Fig. 6 is a fragmentary side elevational view 15 of the stator plate, taken from the right of Fig. 4;

Fig. 7 is a cross sectional view taken on the line 7—7 of Fig. 4;

Fig. 8 is a view taken similarly to Fig. 7 but with the parts of the fastening means unit 20 moved; and

Fig. 9 is a fragmentary sectional elevational view taken on the line 9—9 of Fig. 1.

Referring to these drawings; the stator plate, as shown in Fig. 1, consists of a circular base 1 having an outer marginal rim 2 which projects upwardly into a recess (Fig. 2) formed in the lower end face of the rim of the flywheel 3. The typical cross section of this plate is shown at the right of Fig. 9, such section being modified, 30 as indicated in Fig. 2, where the fastening means, later to be described, are located. The flywheel (Fig. 2) is suitably fixed to the outer end of the crankshaft 4 of an internal combustion engine. The crankcase of the engine supports a stationary pilot flange 5, formed on the outer end of a hub through which the crankshaft 4 passes. This pilot flange has a cylindrical surface 6, and outer and inner end faces 7 and 8, respectively, which are normal to the axis of surface 6. The stator plate 1, has a central recess in its bottom wall (best shown in Fig. 9), which recess has a cylindrical wall 9 of a diameter to closely fit the surface 6 of the pilot flange, and an end wall 10, which is normal to the axis of wall 9 and is 45 adapted to engage the outer end face 7 of the pilot flange. The wall 10 is of annular form, affording a central opening through which the crankshaft 4 passes. The stator plate has fixed thereto, as by screws 11, the usual handle shown in part at 12. This handle extends radially outward beyond the outer periphery of the flywheel 3, thence upwardly (Fig. 5) for a distance and finally radially outwardly. In an outboard motor, the stator plate 1 and flywheel 3 are usually 50 located in a deep well which is surrounded by

55

the fuel-supply tank of the motor, and the handle 12 has to pass upwardly out of this well and thence radially outward above the tank to a position, where it may be conveniently grasped by the operator, as shown for example in the patent, above identified.

The stator plate 1 is held in place on the described pilot flange 5 by one or more identical units. If the pilot flange is relatively short in axial extent, as illustrated herein, at least two fastening units should be used, as indicated herein in order to prevent the stator plate from tilting to any substantial extent on the pilot flange under the downward pressure or the upward pull, which may at times be exerted by the operator on the handle 12. If the pilot flange has sufficient axial length to prevent undue tilting, then a single fastening unit will suffice.

Each fastening unit includes a friction shoe 13 (Figs. 2 and 4) to press on the cylindrical surface 6 of the pilot flange 5 and yieldingly hold the stator plate 1 in the various positions of angular adjustment, to which it may be moved by handle 12, and a spring finger 14 (Figs. 2 and 5) to press against the inner end face 8 of the pilot flange and draw the end wall 10 of the stator plate tightly against the outer end face 7 of the pilot flange. The shoe 13, as shown, is of channel form with inner and outer flanges upstanding from opposite edges of a common base. This shoe and finger are suitably connected together, as by the rivet 15, and are adapted to be moved by the same means in parallel paths in planes normal to the axis of the cylindrical wall 9 toward and away (usually and preferably radially as shown) from such wall. As shown in Fig. 8, the stator plate has a radial groove 16 therein which at its inner end (see also Fig. 4) opens through the wall 9 and at its outer end terminates at the inner face of a lug 17 formed integrally as a portion of flange 2. This groove has vertical side walls 18 (Fig. 8) spaced to freely receive between them (see Fig. 7) the shoe 13. The groove 16 has a radial slot 19 in its bottom wall leaving on each side thereof, flat horizontal surfaces 20, which, as shown in Fig. 7, act as ways to slidably support the shoe 13. The slot 19 communicates at its outer end with a groove 21 in the bottom face of lug 17 (Figs. 2 and 5). Both the slot 19 and groove 21 are of substantially the same width as spring finger 14, the sides of which slidably engage the sides of the slot 19 and groove 21, whereby the finger is prevented from turning. The outer end of spring finger 14, which rides in groove 21, bears against the bottom of lug 17. With its outer end thus supported, the spring finger serves yieldingly to hold the shoe 13 against the ways 20 upon which it slides and prevents tilting of the shoe. This is important in order to hold the inner end of finger 14 in proper position so that it will be flexed downwardly and engaged with the inner end face 8. When the finger 14 is engaged beneath end face 8, the shoe 13 is held more firmly to its ways because of the flexing and tensioning of the inner end of the spring. The spring then has its inner end bearing against face 8, its outer end bearing against the bottom of lug 17 and an intermediate portion held by the shoe 13 bearing on ways 20. The spring finger serves to close the slot 19 and prevent the entry of dust and dirt into the space between the stator plate and flywheel, in which the magneto elements are housed, as will later appear.

The means for moving the shoe 13 and spring finger 14 comprise a screw 22 threaded into lug 17 and having on its outer end a hexagonal head 23 with a screw driver slot 24 therein, both accessible from outside the stator plate. Screw 22 has on its inner end, as an integral part thereof, a coaxial rod 25 of considerably less diameter. The inner end of this rod slides freely through a hole in the outer upstanding part of the channel-shaped shoe 13. Encompassing rod 25 is a coil spring 26, which acts between a shoulder on the rod and the outer face of the aforesaid outer part of the shoe 13 to press the latter inwardly against the surface 6 of the pilot flange. Near its inner end and inwardly beyond the outer flange of shoe 13, rod 25 is circumferentially grooved to receive a snap washer 27, which acts as an abutment to engage the inner face of said upstanding part, when screw 22 is moved outwardly, in order to draw the shoe outwardly away from the cylindrical surface 6.

When screw 22 is retracted as shown in Fig. 3, the washer 27 will abut the inner face of the outer flange of shoe 13 and move it radially outward on its ways 20, the spring 26 then pressing such flange against the washer. The outside diameter of spring 26 is less than the inside diameter of the screw threaded hole in lug 17 so that on retraction of the screw 22, the spring 26 may enter the threaded hole in lug 17. The arrangement is such that the outer face of the outer flange of shoe 13 can never be drawn into abutment with the inner face of lug 17 by means of screw 22. The latter will be entirely unscrewed from lug 17 before such faces can be engaged. Thus, the washer 27 cannot be forced off rod 25 by careless operation of screw 22 beyond its necessary outward limit of movement. If the screw is by inadvertence entirely unscrewed, the parts of the fastening unit will remain assembled and can again be rendered operative by again threading screw 22 into lug 17. When the screw is threaded into the lug 17, the shoe 13 and finger 14 will move with it until the inner face of the inner flange of the shoe engages the cylindrical surface 6. By that time, the inner end of finger 14 will have moved inwardly beyond the periphery of the pilot flange and into engagement with the inner end face 8 of the pilot flange. As the spring finger 14 moves inwardly and engages such surface, it is deflected and placed under stress to draw and thereafter yieldably hold the end wall of the stator plate against the outer end face 7 of the pilot flange. Continued inward movement of the screw 22 will compress the spring 26 to provide the necessary pressure to yieldingly hold the stator plate against rotation on the pilot flange. Thus, by turning the one member, the screw 22, both the shoe 13 and finger 14 will be moved into active holding positions and the stress of the spring 26 can be adjusted, as required. All this can be accomplished from outside the magneto housing, which is afforded by the flywheel and stator plate. Usually, there is a removable plate in the housing around the engine, which allows access to the outer end of screw 22. Sometimes, the latter can be turned by screw driver inserted in slot 24. In other cases, the screw can be turned with an open end wrench engaged with head 23.

The invention, being concerned with the fastening of the stator plate on the pilot flange of the engine crankcase, is independent of the construction and arrangement of the magnetic and

electrical elements of the magneto. The function of the stator plate is to support the stationary magnetic elements and the electrical elements of the magneto, whatever the construction and arrangement of such elements may be, and to enable such elements to be angularly moved relatively to the crankshaft of the engine. Hence, the magneto elements need not be described in detail.

These elements have, however, been indicated in one particular arrangement in the drawings and they will be briefly described. The flywheel, shown in part in Fig. 1, carries a permanent magnet 28 with pole shoes 29 connected one to each polar extremity thereof. The magnet and shoes are fixed in the non-magnetic flywheel 3 during the process of casting the same. In this particular case there are two identical sets of magnetic elements on the stator. Each set includes a laminated iron core structure having three angularly-spaced legs 30, 31 and 32, the inner ends of which are magnetically interconnected and the convex outer ends of which are adapted to magnetically connect successively with the concave inner faces of the pole shoes 29. This core structure is secured, as by screws 33, to suitable pads such as 34 on the stator plate. The central leg 31 bears primary and secondary coils 35 and 36, respectively, herein shown as contained in a molded insulating casing 31, from which emerges a high tension wire 38, passing out through the flange 2 of the stator plate, at a level below the flywheel 3, and adapted for connection to a spark plug of the engine. The breaker mechanism for controlling the circuit of the primary coil 35 includes an arm 39 of insulating material having a breaker point 40 and pivoted at 41 to a metallic support 42, fixed to a pad 43 on the stator plate. This support 42 bears the stationary breaker point 44. The breaker arm 39 is actuated from a cam 45, which is fixed on crankshaft 4, by means of a slide, shown in part at 46, and mounted in the pad 43. The usual condenser is shown at 47 with its insulated terminal connected by a flexible conductor 48 to the breaker point 40. The construction and operation of the magneto is substantially the same as disclosed in the Alstrom and Brownlee Patent No. 2,447,727, granted August 24, 1948 to the assignee of the present application.

The stator plate may be quickly and easily mounted on the engine. With each unit of the fastening means withdrawn to a released position, such as shown in Fig. 3, the plate 1 may be slipped on the pilot flange 5 with its walls 9 and 10 respectively engaging the surfaces 6 and 7 of the pilot flange. The screws 22 are then turned to move the shoes 13 and fingers 14 radially inward. When the shoes 13 engage the surface 6, the fingers 14 will have been moved into engagement with the inner end face 8 of the pilot flange and placed under stress to yieldingly hold the end wall 10 in engagement with the outer end face 7 of the pilot flange. The screws 22 will then be turned farther in the same direction in order to stress the coil springs 26 to the desired degree. The cam 45 is applied to the crankshaft 4 and then the flywheel 3 is fixed to the latter to complete the assembly. Whenever the spring pressure on shoes 13 needs adjustment, this may be effected without removing the flywheel 3 from the engine crankshaft, by using a screw driver or wrench, whichever is most convenient in the particular engine involved, applied to the slot 24 or head 23 of screw 22. The stator plate may easily

be removed from the pilot flange 5 after the flywheel 3 has been removed from the crankshaft 4, by turning the screws 22 to move the shoes 13 and fingers 14 outwardly to released position and then pulling the plate axially off the pilot flange 5. As previously described, the screws 22 can be completely unscrewed without causing any damage. The parts of the fastening unit remain in assembled relation and cannot fall off the stator plate and be lost. The washer 27 cannot be forced off rod 25 by unscrewing screw 22. Each fastening unit may be replaced correctly simply by threading its screw 22 into its lug 17. The location of the two fastening units in the manner shown in Fig. 1 is deemed preferable. One unit is placed as closely as possible to handle 12 so that its finger 14 will by its engagement with the inner end face 8 of the pilot flange most effectively resist tilting of the plate 1 due to any upward pull on handle 12. The other unit is located approximately opposite the handle 12, where its finger 14 can most effectively resist tilting of the plate under downward pressure on the handle. The two units are purposely not located diametrically opposite. If they were so located, the stator plate might easily be tilted about the axis of the aligned friction shoes. Such tilting is prevented by the arrangement shown. The particular pilot flange 5, herein illustrated, is three inches in diameter and has an axial length of three-eighths of an inch. With a clearance of say three thousandths of an inch between the cylindrical surfaces 6 and 9, tilting of the stator plate, to an extent sufficient to throw the polar surfaces of legs 30, 31 and 32 out of true coaxial relation with the pole shoes 29 of magnet 28, would be possible except for the fastening means of this invention. To resist this tilting, the pilot flange 5 is made relatively large in diameter to provide a relatively large area of engagement of end wall 10 with the outer end face 7, and substantial spring pressure is applied by the fingers 14 at two or more points to hold the surfaces 7 and 10 in close contact. The degree of tilting possible decreases as the axial length of the pilot flange increases, other factors being the same. Hence, in installations, where there is room for a pilot flange having an axial length great enough to prevent substantial tilting, a single fastening unit may suffice. The number of fastening units is not of the essence of the invention.

The invention thus provides a fastening means for adjustably holding the stator plate of a flywheel magneto on the pilot flange of an engine crankcase in various positions of angular adjustment with respect to the engine crankshaft and for holding the plate against axial movement on such flange and against tilting thereon, both holding members being movable simultaneously into or out of holding position by a single manually-operable member located outside the magneto housing, such manually-operable member being movable, after the holding members have been moved into holding position, to adjust the spring pressure of the friction-shoe holding member on the peripheral surface of the pilot flange.

What is claimed is:

1. Fastening means for adjustably holding the stator plate of a flywheel magneto on the pilot flange of an engine crankcase, comprising in combination, a stator plate having a recess with a cylindrical wall, adapted to receive and engage the cylindrical surface of such flange, and an end wall normal to the axis of the cylindrical wall,

and adapted to engage an outer end face of the flange; and fastening means consisting of one or more identical units, each comprising a friction shoe mounted on the inner face of the stator plate for movement toward or away from said cylindrical wall in a path normal to said axis and adapted, when moved inwardly, to press on the cylindrical surface of the pilot flange and frictionally hold the stator plate in various positions of angular adjustment on the flange, a spring finger connected to move with the shoe in a parallel path and adapted, when the shoe is moved inwardly, to engage an inner end face of the pilot flange and draw said end wall against said end face and hold the stator plate against axial and tilting movement on the pilot flange, and manually-operable means accessible from the outer face of said plate for moving the connected shoe and finger in their respective paths between an outer position, in which the shoe and finger are respectively disengaged from the cylindrical surface and inner end face of the pilot flange, and an inner position, in which said shoe and finger are respectively engaged with said cylindrical surface and said inner face, said means including a spring adapted to be stressed by continued operation of such means after said shoe has engaged said cylindrical wall.

2. Fastening means for adjustably holding the stator plate of a flywheel magneto on the pilot flange of an engine crankcase, comprising in combination, a stator plate having a recess with a cylindrical wall, adapted to receive and engage the cylindrical surface of such flange, and an end wall normal to the axis of the cylindrical wall and adapted to engage an outer end face of the flange; and fastening means consisting of one or more identical units, each comprising a friction shoe mounted on the inner face of the stator plate for movement toward or away from said cylindrical wall in a path normal to said axis and adapted, when moved inwardly, to press on the cylindrical surface of the pilot flange and frictionally hold the stator plate in various positions of angular adjustment on the flange, a spring finger connected to move with the shoe in a parallel path and adapted, when the shoe is moved inwardly, to engage an inner end face of the pilot flange and draw said end wall against said end face and hold the stator plate against axial and tilting movement on the pilot flange, a screw threaded into the stator plate and having its head located outside the latter, and a spring located between the shoe and screw for transmitting inward movement of the screw to the shoe and connected finger in order to move the shoe to engage said cylindrical surface and the finger to engage said inner end face, said spring being stressed by continued inward movement of the screw after the shoe has engaged said cylindrical surface.

3. Fastening means for adjustably holding the stator plate of a flywheel magneto on the pilot flange of an engine crankcase, comprising in combination, a stator plate having a recess with a cylindrical wall, adapted to receive and engage the cylindrical surface of such flange, and an end wall normal to the axis of the cylindrical wall and adapted to engage an outer end face of the flange; and fastening means consisting of one or more identical units, each comprising a friction shoe mounted on the inner face of the stator plate for movement toward or away from said cylindrical wall in a path normal to said axis and

adapted, when moved inwardly, to press on the cylindrical surface of the pilot flange and frictionally hold the stator plate in various positions of angular adjustment on the flange, a spring finger connected to move with the shoe in a parallel path and adapted, when the shoe is moved inwardly, to engage an inner end face of the pilot flange and draw said end wall against said end face and hold the stator plate against axial and tilting movement on the pilot flange, a screw threaded into the stator plate and having its head located outside the latter, a spring located between the shoe and screw for transmitting inward movement of the screw to the shoe and connected finger in order to move the shoe to engage said cylindrical surface and the finger to engage said inner end face, said spring being stressed by continued inward movement of the screw after the shoe has engaged said cylindrical surface, an extension on the screw slidably engaged with the shoe for free inward movement during stressing of said spring, and a shoulder on said extension for abutment with said shoe when the screw is moved outwardly in order to move the shoe and its connected finger outwardly out of engagement with the pilot flange.

4. In a stator plate for a flywheel magneto, such plate having a recess with a cylindrical wall adapted to receive and engage the cylindrical surface of a pilot flange on the crankcase of an internal combustion engine and an end wall normal to the axis of said cylindrical wall and adapted to engage an outer end face of said flange, said plate having an upstanding member adjacent its outer periphery and a radially-directed slideway between the inner face of said member and the cylindrical surface of the pilot flange, a screw threaded through said member with its head located outside the latter, a rod of less diameter than the screw fixed coaxially of and to the inner end of the screw and extending along and parallel with said slideway, a friction shoe slidably engaged with the slideway and having an inner portion to engage said cylindrical surface and an outer upstanding part in which the inner end of said rod is slidably engaged, a spring coiled around the rod and located between the outer face of said part and the inner end of the screw, an abutment on the inner end of said rod for engaging the inner face of said part when the screw is moved outwardly, and a spring finger connected to move with said shoe and adapted to engage an inner end face of the pilot flange when said shoe engages said cylindrical surface to hold said end wall against the outer end face of the pilot flange and prevent axial movement or tilting movement of the stator plate on said flange.

5. In a stator plate for a flywheel magneto, such plate having a recess with a cylindrical wall, adapted to receive and engage the cylindrical surface of a pilot flange on the crankcase of an internal combustion engine, and an end wall normal to the axis of said cylindrical wall and adapted to engage an outer end face of said flange, said plate having an upstanding member adjacent its outer periphery and a radially-directed slideway between the inner face of said member and the cylindrical surface of the pilot flange, a screw threaded through said member with its head located outside the latter, a rod of less diameter than the screw fixed coaxially of and to the inner end of the screw and extending along and parallel with said slideway, a friction shoe slidably engaged with

the slideway and having an inner portion to engage said cylindrical surface and an outer upstanding part in which the inner end of said rod is slidably engaged, a spring coiled around the rod and located between the outer face of said part and the inner end of the screw, an abutment on the inner end of said rod for engaging the inner face of said part when the screw is moved outwardly, said plate having a slot therethrough parallel with and adjacent said slideway, a spring finger having an inner end adapted to move into or out of engagement with an inner end face of the pilot flange, said spring finger when its inner end is so engaged filling said slot and closing the same, and a connection

between the finger and shoe extending through said slot for moving both the shoe and finger by said screw.
